UNITED STATES PATENT OFFICE

GLENN E. McFADDEN, OF DETROIT, MICHIGAN, ASSIGNOR TO LINCOLN MANUFACTURING COMPANY, OF DETROIT, MICHIGAN, A CORPORATION OF MICHIGAN

DESIGN FOR A LIGHTING-FIXTURE CHANDELIER OR THE LIKE

Application filed November 15, 1930. Serial No. 37,678. Term of patent 7 years.

To all whom it may concern:

Be it known that I, GLENN E. McFADDEN, a citizen of the United States, residing at Detroit, county of Wayne, State of Michigan, have invented a new, original, and ornamental Design for a Lighting-Fixture Chandelier or the like, of which the following is a specification, reference being had to the accompanying drawing, forming part thereof.

Fig. 1 is a perspective of my lighting fixture.

Fig. 2 is a plan of my lighting fixture looking upwardly at it.

I claim:

The ornamental design for a lighting-fixture chandelier or the like as shown.

GLENN E. McFADDEN.
